FIG. 1

FIG. 2

FIG. 3

FIG. 4

FIG. 5

FIG. 6

FIGURE 1 is a top plan view of a time lock cigarette case, showing my new design.

FIGURE 2 is a bottom plan view.

FIGURE 3 is a side view as seen from the left in FIGURE 1.

FIGURE 4 is a side view as seen from the right in FIGURE 1.

FIGURE 5 is an end view as seen from the top in FIGURE 1.

FIGURE 6 is an end view as seen from the bottom of FIGURE 1.

FIGURE 7 is a perspective view of the open time lock cigarette-case.

The dominant features of my design reside in the combination on the time locked cigarette case disclosed of

the two end-wise hinged sections having cigarette storage compartments on each side of the hinge together with a knob actuated timing lock on one of the open ends and a cylindrical window inset in the opposite open end, the window enclosing the knob and through which the dial is exposed, all as shown.

I claim:

The ornamental design for a time lock cigarette case, substantially as shown and described.
